UNITED STATES PATENT OFFICE.

STEELE F. ROBERTS, OF ALLEGHENY, PENNSYLVANIA.

DESIGN FOR A SPOON.

SPECIFICATION forming part of Design No. 20,712, dated May 5, 1891.

Application filed March 17, 1891. Serial No. 385,427. Term of patent 7 years.

To all whom it may concern:

Be it known that I, STEELE F. ROBERTS, a resident of Allegheny city, in the county of Allegheny and State of Pennsylvania, have invented a new and original Design for Forks, Spoons, Button-Hooks, &c.; and I do hereby declare the following to be a full, clear, and exact description thereof.

My design consists, essentially, in a spoon having the figure of a block house formed in the bowl thereof.

In the accompanying drawing, which illustrates my design in the bowl *a*, which may be

of any desired shape, is the figure of a block house, as at *b*, the figure illustrated having the door *c* and sloping roof *d*, and around the house are a series of port-holes.

What I claim is--

The design for the bowl of spoons herein shown and described.

In testimony whereof I, the said STEELE F. ROBERTS, have hereunto set my hand.

STEELE F. ROBERTS.
